UNITED STATES PATENT OFFICE.

JOSEPH A. RAYMOND, OF CHICAGO, ILLINOIS.

COLLAPSIBLE CANDLE-HOLDER.

1,316,108.

Specification of Letters Patent. Patented Sept. 16, 1919.

Application filed April 7, 1919. Serial No. 288,036.

To all whom it may concern:

Be it known that I, JOSEPH A. RAYMOND, a citizen of the United States, and a resident of Chicago, in the county of Cook and State of Illinois, have invented certain new and useful Improvements in Collapsible Candle-Holders, of which the following, when taken in connection with the drawings accompanying and forming a part hereof, is a specification.

This invention relates to a holder which is designed to be used principally on funeral occasions, for the holding of candles of considerable size in a well elevated position; a plurality thereof being usually required.

Among the objects of this invention are to obtain a holder of the kind recited which, when "set up" on a floor will be of good appearance; not liable to collapse or be overthrown; which can be readily and easily collapsed when not resting on the floor; which is made of few parts; not liable to break or get out of order.

In the drawings referred to Figure 1 is an elevation of the device, collapsed.

Fig. 2 is an elevation of the device "set up."

Fig. 3 is a vertical section of the device in a "set up" condition.

Fig. 4 is an elevation of a portion of the leg members of the device, and the members connected thereto, showing the connecting members, and

Fig. 5 is a perspective of the connecting members between the cylindrical elements of the device.

A reference character applied to designate a given part indicates said part throughout the several figures of the drawings wherever the same appears.

A represents a cylinder and B an additional cylinder which is slidably joined to cylinder A. C represents a flaring or conical end which is joined to the lower end of cylinder A by the bead a. A' represents a bead near the upper end of said cylinder A. b represents a slot which extends from near one end of cylinder B, and b' a bead at the upper end thereof. C' represents a flaring end or a truncated cone which is attached to the upper end of the cylinder B by bead b'. D represents a candle stick holder, and d the base thereof, which is removably set in flaring end C. E, E, E, represent leg members, which are, respectively, longitudinally movable in guides or slides, one thereof

being illustrated in Figs. 3 and 4, and lettered F. Guides F, F, F, are secured to the under side of conical end C. e, e, e, represent the bases or feet of leg members E, E, E. G represents a member which is movable in cylinder A. H represents rollers on the upper ends of leg members E, E, E. I, I, I, represent runways, which are illustrated in Fig. 4 as slots in members J, J, J, and said members are rigidly attached to the under side of movable member G. Rollers H, H, H, are illustrated as rotatably mounted on wires K, K, K, and said wires are, respectively, secured to the leg members by turning the sides or edges of said members over onto said wires, as at g, g, g. L represents a member which is rigidly secured at its lower end to member G and at its upper end to rack member M. M, M', are rack members. Member M is longitudinally movable in a guide or slide, (M''), which is illustrated in Fig. 5. Guide M'' and rack M' are attached to cylinder B. Rack members M, M', are illustrated as substantially duplicates, respectively made of sheet metal which is formed up to obtain edges m, m; and perforated to obtain a number of apertures m', arranged at regular intervals, the spaced relation thereof corresponding with the spaced relation of the teeth on gear wheel N, and to engage therewith, in the same manner as the teeth of a rack intermesh with those of a gear wheel. Gear wheel N is loosely mounted on shaft n, (Figs. 3 and 5), and is held in place by tubes P, P. The shaft is held in place in cylinder A by screws n', n'; which extend through slot b; said slot limiting the length of travel of said cylinders A and B relative to each other.

The slot b enables me to place the shaft n nearer the upper end of cylinder A than could otherwise be done; and Q represents an ornamental member which is secured in place on the cylinder A, by screws n', n'; and extend upwardly therefrom with the upper end provided with bead R which forms an annular groove in which is placed the member S. Member S is made by me of leather, its function being to prevent noise and scratching of the outer surface of the cylinder B as the cylinders are drawn out or forced together. Member Q is illustrated as a two part cover to slot b, and consists of truncated cones the larger ends meeting and secured together by flange q

on one part and bead q' on the other part. The lower end of the lower part member Q is cylindrical fitting closely to cylinder A, with the end thereof abutting against bead 5 a' , to give a finished appearance to the device; and making said lower end accord in appearance with bead R at the upper end of said member.

The operation of the apparatus is,—assuming it to be in a collapsed condition as illustrated in Fig. 1;—the cylinder B is drawn out of the cylinder A. In drawing cylinder B out from cylinder A the rack member M' turns gear wheel N, and said 10 wheel forces rack member M longitudinally in guide M'; and member L being attached to said rack member and to member G said member G is moved toward the flaring end C. Said movement of member G forces the 15 leg members E, E, E, in slides F, longitudinally; that is, from the position in which they are illustrated in Fig. 1 into the position in which they are illustrated in Fig. 2. The apparatus is then set on the 20 floor. As leg members E, E, E, move longitudinally in guides F, F, F, the rollers H, H, H, travel in runways I, I, I, of members J, J, J.

So long as the apparatus is standing on a 25 floor it cannot be collapsed, as the angles at which the leg members are held causes them to bear upwardly against the underside of the flaring member C in such manner that they will not move longitudinally in guide 30 members F, F, F. To collapse the apparatus it is lifted from the floor and the cylinders A, B, are forced together. Leg members E, E, E, are thereby drawn back 35 from the position in which they are illustrated in Fig. 2 into the position in which they are illustrated in Fig. 1. The movement of the rack members M, M', and gear 40 wheel N causes the drawing in of the leg members, as described.

45 I claim:

1. A cylinder, a movable element, leg members, means to control the direction of movement of said leg members and means to connect said movable element to said leg members, in said cylinder, in combination with an additional cylinder slidably joined to said first named cylinder, and means connecting said additional cylinder to said movable element, so that on said additional cylinder being moved in one direction said 50 movable element is moved in the opposite direction relative to said first named cylinder.

55 2. A collapsible candle holder comprising

a cylinder, a gear rack secured to and a 60 rack guide secured in said cylinder, and an additional gear rack longitudinally movable in said guide, in combination with an additional cylinder slidably joined to said first named cylinder, guides to said additional cylinder at one end thereof, leg members longitudinally movable in said guides, a 65 movable member in said additional cylinder, connections between said movable member and said leg members and a connection between said movable members and said movable rack, and a gear wheel rotatably mounted in said additional cylinder to engage with said racks.

3. A cylinder, a movable element, leg 75 members and means to control the direction of movement thereof, a connection between said element and said leg members, said connection comprising runways and rotatably mounted rollers arranged to travel in said 80 runways, in combination with an additional cylinder, and means connecting said additional cylinder and said movable element, said means comprising a rotatably mounted gear wheel and racks thereto, said racks attached respectively to said additional cylinder 85 and to said movable element.

4. A collapsible holder comprising a cylinder, and a gear wheel rotatably mounted therein, in combination with an additional 90 cylinder and a body having a cylindrical wall slidably fitting in said cylinder at opposite ends thereof, rack members respectively attached to said additional cylinder and said body, and engageable with said 95 gear wheels, and longitudinally movable leg members connected to said body.

5. A collapsible holder comprising a cylinder, a flaring end attached to said cylinder and a gear wheel rotatably mounted 100 in said cylinder, in combination with guides in said flaring ends, an additional cylinder and a body having a cylindrical wall slidably fitting in said first named cylinder at the end opposite said wheel, rack members 105 respectively attached to said additional cylinder and said body and engageable with said gear wheel on opposite sides thereof to transmit movement in opposite directions, leg members longitudinally movable in said 110 guides, rollers on the ends of said leg members, and runways for said rollers on said body.

JOSEPH A. RAYMOND.

In the presence of—

CHARLES TURNER BROWN,
E. A. WINCHELL.
